CLAIM

I claim the ornamental design for a field stretcher, as shown and described.

DESCRIPTION

FIG. 1 is a side perspective view of a field stretcher embodiment showing our new design;

FIG. 2 is a top elevation view of the field stretcher embodiment thereof;

FIG. 3 is a bottom elevation view of the field stretcher embodiment thereof;

FIG. 4 is a side elevation view of the field stretcher embodiment thereof, the opposite side view being the same;

FIG. 5 is a bottom edge elevation view of the field stretcher embodiment thereof;

FIG. 6 is a top edge elevation view of the field stretcher embodiment thereof;

FIG. 7 is a top perspective view of the field stretcher embodiment of FIG. 1;

FIG. 8 is a side perspective view of a field stretcher embodiment showing our new design;

FIG. 9 is a top elevation view of the field stretcher embodiment thereof;

FIG. 10 is a bottom elevation view of the field stretcher embodiment thereof;

FIG. 11 is a side elevation view of the field stretcher embodiment thereof, the opposite side view being the same;

FIG. 12 is a bottom edge elevation view of the field stretcher embodiment thereof;

FIG. 13 is a top edge elevation view of the field stretcher embodiment thereof; and,

FIG. 14 is a top perspective view of the field stretcher embodiment of FIG. 1.

Broken lines or dotted sections in any of the foregoing Figures are for illustrative purposes only and form no part of the claimed design.

The front and back elevation views of the design may appear dissimilar in length due to the material used in its construction that has a naturally tendency to bunch or gather at one end in different amounts when laid flat on its opposite sides. The front and back elevation views of the design may appear dissimilar in width due to the material of the field stretcher and an arbitrary distance shown between the edges of the field stretcher along its length in the top elevation view when

(Continued)

laid flat and that of an arbitrary distance shown between the edges of the field stretcher along its length in the bottom elevation view.
